UNITED STATES PATENT OFFICE.

WELCOME F. SWEET, OF ST. LOUIS, MISSOURI, ASSIGNOR TO THE METAL NOVELTY COMPANY, OF ST. LOUIS, MISSOURI, A CORPORATION OF MISSOURI.

RAZOR-BLADE-SHARPENING MACHINE.

1,086,481.

Specification of Letters Patent. Patented Feb. 10, 1914.

Application filed November 20, 1911. Serial No. 661,405.

To all whom it may concern:

Be it known that I, WELCOME F. SWEET, a citizen of the United States, residing at St. Louis, Missouri, have invented a certain 5 new and useful Improvement in Razor-Blade-Sharpening Machines, of which the following is a full, clear, and exact description, such as will enable others skilled in the art to which it appertains to make and use 10 the same, reference being had to the accompanying drawings, forming part of this specification, in which—

Figure 1 is a top plan view of a razor blade sharpening machine of my improved 15 construction. Fig. 2 is an enlarged transverse section taken approximately on the line 2—2 of Fig. 1. Fig. 3 is a plan view of a gear box that is positioned on the under side of the central portion of the machine 20 and which gear box contains the cam which controls the stropping belt reversing mechanism. Fig. 4 is a vertical section taken through the center of the gear box seen in Fig. 3 and also showing a part of the bed 25 plate of the machine. Fig. 5 is a side elevation of my improved machine. Fig. 6 is an enlarged detailed section taken approximately on line 6—6 of Fig. 1 and illustrating one of the detachable safety razor blade 30 holders utilized in connection with my improved machine. Fig. 7 is an enlarged cross section taken approximately on the line 7—7 of Fig. 6. Fig. 8 is a cross section taken approximately on the line 8—8 of Fig. 6. Fig. 35 9 is an elevation of a holder particularly designed for holding ordinary razor blades while the same are being honed or stropped. Fig. 10 is an enlarged cross sectional view taken approximately on the line 10—10 of Fig. 9.

This invention relates to a machine for sharpening razor blades and the principal object of my invention is to provide a comparatively simple, inexpensive machine, 45 which is adapted to receive and sharpen by honing and stropping all forms of razor blades.

Further objects of my invention are to provide a machine which will simultaneously hone and strop a number of razor blades, to equip a razor stropping machine with a hone which can be used for sharpening razor blades which are exceedingly dull, to provide a machine with an endless strop 50 which operates over a pair of pulleys, to

provide means for automatically reversing the movement of the endless strop and at the same time to shift the blade holders so as to alternately bring the side faces of the blades into contact with the strop, and to provide 60 simple blade holders which can be readily positioned upon or removed from the machine.

With the above objects in view, my invention consists in certain novel features of construction and arrangement of parts herein-after more fully described and claimed.

Referring by numerals to the accompanying drawings, 1 designates the bed plate of the machine which is supported on suitable 70 legs, or a frame work 2, and formed on or fixed to this bed plate adjacent one end is a pair of standards 3, provided at their upper ends with bearings 4 which receive the trunnions of a roller 5.

Arranged for sliding movement between a pair of ribs 6 on the opposite end of the machine is a plate provided with a pair of uprights 7, and formed in the upper ends of this upright are bearings 8, which receive 80 the trunnions of a roller 9. The diameter of this roller equals that of the roller 5 and formed on or fixed to the ends of this roller are grooved pulleys 10.

The plate carrying the standards 7 is 85 moved backward and forward by means of a screw rod 11, thereby varying the distance between the rollers 5 and 9, and thus said screw rod performs the function of a belt 90 tightener for the belt or endless strop 12 which operates on the rollers 5 and 9. This endless strop is preferably made of leather suitable for stropping razor blades, or, if desired, it may be made up of two or more layers of flexible material with a leather 95 facing on one side and fabric facing on the other. The inner face of this strop is used for finishing the razor blades and said inner face is maintained in a perfectly smooth condition by reason of its constant operation over the smooth, hard surfaces of the rollers 5 and 9.

The outer face of the endless strop is used in the first stropping operations and this outer face can be treated with a suitable material which is particularly adapted for sharpening blades during the stropping operations.

Formed on or fixed to the under side of the plate 1, immediately below the standards 110

- 3 a pair of depending ears 13, in which is journaled a shaft 14 and fixed on the center thereof is a pulley 15 which is adapted to receive a belt 16 operated by a suitable motor.
- 5 Loosely mounted on the shaft 14 on one side of the pulley 15 is a belt wheel 17 provided on its outer edge with a grooved pulley 18 and loosely mounted on the shaft 14 on the opposite side of the centrally arranged 10 pulley 15 is a second belt wheel 19 carrying on its outer edge a grooved pulley 20.
- 15 21 designates brackets which are arranged to slide lengthwise on the under side of the plate 1 below the plate carrying the uprights 7 and these brackets are moved backwardly and forwardly by screw rods 22. Journaled in the lower portion of these brackets is a shaft 23 and loosely mounted thereon are grooved pulleys 24 which occupy the same 20 vertical planes with the corresponding grooved pulleys 10, 18 and 20.
- 25 Loosely mounted on a shaft on the under side of the plate 1 in front of the bracket 21 is a pair of grooved pulleys 26 which are in alignment with the pulleys 24.
- 30 27 designates a belt which passes around the grooved pulley 20, beneath the corresponding pulley 24, thence upward through a suitable opening formed in the plate 1 over the corresponding grooved pulley 10, thence downward through an opening suitably formed in the plate 1, thence beneath the corresponding pulley 26 and from thence to and over the pulley 20. A corresponding 35 belt 28 extends over the top of the grooved pulley 18, downward beneath the corresponding pulley 24, thence upward over the corresponding pulley 10, thence downward beneath the corresponding one of the pulleys 26 and from thence to the under side of 40 and around the pulley 18. It will be noted that this belt 28 crosses between the pulleys 24 and 26 and the pulley 18, and thus the movement imparted to the roller 9 by said 45 belt 28 is reverse to the movement imparted by the belt 27.
- 50 The belt 16 is alternately shifted from the belt wheel 17 to the belt wheel 19, and vice versa, and as a result the rotary motion imparted to the roller 9 is reversed at regular intervals and consequently the motion of the endless strap is correspondingly reversed.
- 55 Removably positioned on the under side of the central portion of the plate 1 is a box or housing 29 and journaled in the bottom thereof is the lower end of a shaft 30 which extends upward through the plate 1, said shaft being provided on its upper end with 60 a grooved pulley 31. Fixed on the lower portion of this shaft within the box 29 is a worm wheel 32 with which engages a worm 33 carried by a shaft 34, which latter is journaled in suitable bearings formed in the 65 wall of the box 29, and fixed on the outer end of this shaft 34 is a grooved pulley 35. Fixed on the end of the shaft 14 in alignment with the pulley 35 is a grooved pulley 36 and connecting these pulleys 35 and 36 is a belt 37.
- 70 The mechanism just described provides for imparting constant rotary movement from the driven shaft 14 to the upright shaft 30. Fixed on the shaft 30 above the worm wheel 32 is a disk 38 in the edge of which is formed a recess 38^a and positioned immediately over the disk and loosely mounted on the shaft 30 is a large disk 39 provided in its top surface with a cam groove 39^a. The lower edge of this disk 39 is supported on a suitable flange 29^a which is a part of the box 29, and formed in the edge of this disk 39 is a horizontally disposed recess 40 in which is arranged to slide a headed pin 40^a, the point of which is adapted to enter the recess 38^a. A compression spring 40^b is positioned on this pin 40^a, beneath the head thereof and the tendency of this spring is to withdraw the point of the pin from the recess 38^a.
- 75 80 85 90 95 100 The means utilized for forcing the point of the pin 40^a into the recess 38^a to lock the disk 39 to the disk 38 comprises a pin 41 operating through the side wall of the box 29 and which pin is carried by the end of a horizontally disposed arm 42 and located upon the pin 41 between the wall of the box and the end of this arm is a compression spring 43. The opposite end of the arm is carried upon the lower end of a vertically disposed shaft 44 which is journaled in a suitable bearing formed on the plate 1, and fixed to the upper end of this shaft is a handle 45 which extends to the side of the plate 1 and is provided in its under side with a pin 45^a which is adapted to engage in either one of a pair of apertures 45^b formed in the top of the plate 1.
- 105 110 115 120 125 130 The construction just described provides means for shifting the pin 41 inwardly to force the headed pin 40^a inwardly and the pin 45^a provides means for locking the handle 45 in either one of its positions.
- 120 Fulcrumed on a stud on the under side of the plate 1 adjacent the box 29 is a bell crank 110 lever 46 provided with an arm 46^a which projects through an opening suitably located in the side walls of the box 29 and the end of said arm is provided with a depending pin 46^b which extends into and traverses the 120 groove 39^a in the disk 39. A second arm 46^c of this bell crank extends laterally beneath the plate 1 and is pivotally connected to a longitudinally moving rod 47 which is for the purpose of shifting positions of the blade 125 holders as hereinafter more fully described. A third arm 46^d projects outwardly beneath the end of the plate 1 and is for the purpose of imparting movement to a series of blade 130 holders which are adapted to maintain the

razor blades upon a reciprocating hone located at the end of the machine and herein-after more fully described.

Located to one side of the stropping belt and projecting upwardly from the plate 1 is a frame 48 and projecting horizontally therefrom in a plane just above the top surface of the upper half of the endless strop 12 is a series of tubular bearings 48^a. A corresponding row of bearings extend inwardly from a rail 48^b immediately above the top or inner surface of the lower half of the flexible strop 12. Arranged for rotation in the bearings 48^a is a series of tubular sockets 49, each provided on its outer end with a crank arm 49^a and projecting outwardly from the outer end of each of these arms is a pin 49^b. A corresponding series of tubular sockets are in the bearings formed on the bar 48^b and this second set of sockets are provided on their outer ends with crank arms 49^a, the same carrying pins 49^b.

As hereinbefore stated, the outer end of the arm 46^c of the bell crank 46 is pivotally connected to a longitudinally disposed rod 47 which slides lengthwise in bearings 47^c on the under side of the plate 1 and projecting upwardly from the ends of this rod through suitable openings formed in the plate 1 are uprights 50 which are positioned adjacent the frame 48. Formed on or fixed to the upper portions of these uprights 50 are short rack bars 50^a which project inwardly toward one another and a corresponding pair of rack bars 50^b extend inwardly from the uprights in approximately the same plane with the rail 48^b.

Pinions 51 are journaled on the outside of the frame 48 at the upper corners thereof and these pinions mesh with the teeth of the rack bars 50^a.

Fixed to the outer faces of these pinions are crank arms 51^a and journaled upon pins 51^b carried by said crank arms is a longitudinally disposed bar 51^c, the top of which is notched as designated by 51^d to receive the pins 49^b on the crank arms 49^a. Retractile coil springs 52 are connected to the pins 49^b and to the bar 51^c, and thus said pins 49^b are yieldingly held in their respective notches.

Pinions 53 are journaled on the sides of the frame 48 at the ends of the rail 48^b and carried by said pinions are short crank arms 53^a, the outer ends of which are provided with pins 53^b which are journaled in the ends of a longitudinally extending bar 53^c. The upper edge of this bar is notched to receive the pins 49^a on the cranks 49^a and retractile springs 53^d are connected to the pins 49^a for the purpose of yieldingly holding the same in their respective notches.

The device used for engaging the razor blades while they are in the machine consists of a bar 54 approximately semi-circular in cross section and formed integral

with one end of this bar is a stem 54^a which is adapted to be inserted in the tubular sockets which are mounted in the bearings 48^a and the bearings on the bar 48^b. The end of each tubular socket is notched as designated by 54^b to receive a corresponding lug or shoulder on the end of the bar 54 and thus said bar or pin will rotate or rock with the tubular socket. Hinged to the inner end of each bar 54 is a plate 55 which is semi-circular in cross section and fixed in any suitable manner to the bars 54 and 55 are spring fingers 55^a arranged in pairs and adapted to engage and clamp the razor blades to be sharpened. The free end of the bar 55 is clamped to the corresponding end of the bar 54 by a tubular keeper 55^b which is mounted for rotation on the end of the bar 54 and a portion of said tubular keeper is cut away as designated by 55^b so as to permit the free end of the bar 55 to swing open when it is desired to insert or remove the razor blades.

For the purpose of honing the razor blades on a stone before they are stropped on the flexible member 12, I utilize a hone 56 which is positioned in a holder 56^a and depending from the under side of this holder is a pair of pins 56^b, the lower ends of which are journaled in disks 56^c, one of which is provided in its periphery with a groove to receive a belt 56^d which is connected to and driven by the pulley 31. The disks 56^c are supported on vertically disposed shafts 57, the lower ends of which are journaled in a plate 57^a.

Extending from one end of the plate 1 and fixed on the shafts 57 are small grooved pulleys 57^b around which passes a belt 57^d. Located on this end of the table is an upright frame 58 provided with a series of tubular bearings 58^a in which are journaled sockets 58^b, each provided with a crank arm 58^c and the latter provided with a pin 58^d. A notched bar 59 receives the pins 58^d, said bar being journaled on crank arm 59^a carried by pinions 59^b and these pinions are actuated by racks 59^c carried by a transversely moving frame 59^d, the lower portion of which extends through suitable openings formed in the plate 1, and said lower portion is pivotally connected to the end of the arm 46^d of the bell crank.

An arm 60 projects downwardly from the central portion of the bell crank 46 and seated in the outer end of this arm is a pair of pins 60^a which are positioned on each side of the driving belt 16.

The holder for razor blades which are provided with handles, as shown in Fig. 9, comprises a rod 61 having a pin 62 on one end which pin is adapted to engage in the tubular sockets and fixed to this rod is a spring clip 63 which is adapted to receive and hold razor blades of the ordinary type. Set

screws 64 are seated in the rod 61 adjacent the ends of the clip 63 for the purpose of adjusting the position of the razor blade with respect to the rod 61, and located on 5 said rod adjacent its outer end is a spring clip 65 which is adapted to engage and hold the razor handle.

The operation of my improved sharpening machine is as follows: The belt 16 is 10 driven and normally travels upon the tight pulley 15 and as this pulley is operated the belt 37 operating on the pulleys 36 and 35 imparts rotary movement to the shaft 34 carrying the worm 33 which meshes with 15 the worm wheel 32. Normally the spring 43 holds the end of the pin 41 away from the headed pin 40^a and the spring behind the last mentioned pin normally holds the point of the same out of the recess 38^a and 20 therefore the disk 38 rotates with the shaft 30 independently of the disk 39. The blades to be sharpened are positioned between the pairs of spring fingers 55^a and the pins 54^a of the blade holders are inserted in the tubular 25 sockets mounted in the bearings 48^a and in the bearings on the rail 48^b. The operator now engages the handle 45 and manipulates the same so as to swing the end of the arm 42 inwardly, thereby forcing the pin 41 30 against the headed pin 40^a and when the disk 38 is rotated so that the recess 38^a is brought into alignment with the headed pin, the point thereof engages in said recess, thereby locking the disk 39 to 35 the disk 38. The pin 45^a on the handle 45 is now engaged in one of the recesses 45^b, thus locking the parts in their shifted positions. As the disk 39 provided with a cam groove 39^a rotates with the disk 38 and the pin 40 40 46^b in the arm 46^a of the bell crank traverses the cam groove, thereby rocking the bell crank 46, the pins 60^a on the end of the arm 60 engage the belt 16 and alternately shift the same from the tight pulley 15 on 45 to the loose rollers 17 and 19. The belts 27 and 28 operating on the grooved pulleys 18 and 20 are intermittently driven in opposite or reverse directions, and as said belts pass around the grooved pulleys on the ends of 50 the roller 9, said roller is intermittently driven in opposite directions, thereby imparting corresponding movement to the flexible strop 12. In other words, the various connections are arranged so that when 55 the belt is running on the roller 17, the flexible strop is moving in one direction, and when the belt is shifted on to the roller 19, the flexible strop is driven in the opposite direction. During the short period of time 60 required to effect the reverse movement of the flexible strop, the blade holders are all rocked so as to reverse the positions of the blades with respect to the flexible strop, which action is brought about by the swing- 65 ing movement of the arm 46^c of the bell

crank which is imparted to the rod 47. This rod is mounted for sliding movement in bearings 47^x and the uprights 50 carried by said rod are moved a short distance lengthwise and the racks 50^a and 50^b carried by 70 said uprights impart partial rotary movement to the pinions 51 and 53 and the bars 51^c and 53^c carried by the crank arms 51^a and 53^a are simultaneously elevated and shifted lengthwise which movement imparts 75 a swinging movement to all of the crank arms 49^a and 49^c, thereby partially rocking all of the sockets 49 and consequently imparting partial rotary movement to the blade holders so that the blades carried 80 thereby are intermittently reversed upon the flexible strop, thereby bringing both sides of the edges into engagement therewith. The coil springs 52 and 53^d provide means whereby the edges of the blades are yieldingly held in engagement with the surfaces of the flexible strop. As hereinbefore stated, the outer face and surfaces of the flexible strop can be treated with a compound which is effective in producing sharp edges on the 85 blades, and for this reason the dull razor blades are positioned in holders which are applied to the top row of the tubular sockets and after the blades have been sufficiently stropped by the outer surface of the 90 flexible strop, the blades in their holders are transferred to the lower row of sockets and thus the edges of the blades are finished on the smooth finishing inner surface of the flexible strop, which, as heretofore stated, is 95 maintained in a smooth condition by reason of its travel on the hard surfaces of the rollers 9 and 5. The belt 56^e driven from the grooved pulley 31 and the belt 57^d imparts movement to the disks 56^c, and in turn 100 the hone 56 which is mounted upon said disks is reciprocated. The ends of the blade holders are inserted in the tubular sockets within the bearings 59 and the surfaces of the blades adjacent the edges are brought 105 into contact with the surface of the hone. During the reciprocation of this hone, the blade holders are rocked to reverse the positions of the blades by the arm 46^a of the bell crank which is connected to the lower 110 portion of the frame 59^c.

A razor blade sharpening machine of my improved construction is comparatively simple, can be operated with little power, is adapted to sharpen all forms of razor blades 120 and the blade holders can be easily and quickly shifted from one side of the sockets to the other as required to thoroughly sharpen and finish the edges of the blades.

By providing a hone and utilizing the 125 same in connection with the stropping means, the machine is adapted to sharpen razor blades which are exceedingly dull.

It will be readily understood that minor changes in the size, form and construction of 130

the various parts of my improved razor blade sharpening machine can be made and substituted for those herein shown and described without departing from the spirit 5 of my invention, the scope of which is set forth in the appended claims.

I claim:

1. In a machine of the class described, the combination with an endless flexible strop, 10 of automatically operating means for moving said strop in opposite directions and reversible blade holders adapted to hold the edges of the blades against the inner and outer surfaces of said strop.
- 15 2. In a machine of the class described, the combination with an endless flexible strop, of reversible blade holders adapted to hold the edges of the blades against the inner and outer surfaces of said strop, and automatically 20 operating driving means for intermittently moving the strop in reverse direction.
- 25 3. In a machine of the class described, the combination with an endless flexible strop, of reversible spring-held blade holders adapted to maintain the edges of the blades against the inner and outer surfaces of said 30 strop, and automatically operating means for reversing the positions of all of the blade holders.
- 35 4. In a machine of the class described, the combination with an endless flexible strop, of reversible blade holders adapted to hold the edges of the blades against the inner and outer surfaces of said strop, automatically 40 operating driving means for intermittently moving the strop in reverse directions, and automatically operating means for reversing the positions of all of the blade holders.
- 45 5. In a machine of the class described, an endless strop, automatically operating driving means for intermittently moving the strop in reverse directions, and means for holding a series of razor blades in contact with the surfaces of said strop.
- 50 6. In a machine of the class described, an endless strop, automatically operating driving means for intermittently moving said strop in opposite directions, means for holding razor blades in contact with the surfaces of said strop, and automatically operating means for shifting the positions of the blade holding means at the ends of the intermittent movements imparted to said strop.
- 55 7. In a machine of the class described, a pair of rollers, an endless strop operating thereon, automatically operating driving means for intermittently imparting reverse rotary movement to the rollers and the strop operating thereon, means for holding a series of razor blades against the outer face of the flexible strop and means for holding a series of razor blades against the inner face of said flexible strop.

8. In a machine of the class described, a pair of rollers, an endless strop operating thereon, means for holding a series of razor blades against the outer face of the flexible strop, means for holding a series of razor blades against the inner face of said flexible strop, and automatically operating driving 65 means for intermittently imparting reverse rotary movements to the rollers and strop carried thereby.

9. In a machine of the class described, a pair of rollers, an endless strop operating 75 thereon, automatically operating driving means for intermittently rotating the rollers in reverse directions, means for holding a series of razor blades against the outer face of the flexible strop, means for holding 80 a series of razor blades against the inner face of said flexible strop, and automatically operating means for simultaneously reversing the positions of the blade holding means.

10. In a machine of the class described, a pair of rollers, an endless strop operating thereon, means for holding a series of razor blades against the outer face of the flexible strop, means for holding a series of razor blades against the inner face of said flexible 90 strop, automatically operating driving means for intermittently imparting reverse rotary movements to the rollers and strop carried thereby, and automatically operating means for simultaneously reversing the position of the blade holding means.

11. In a machine of the class described, a pair of rollers, a flexible strop operating on said rollers, automatically operating driving means for intermittently rotating one of the rollers in opposite directions, a row of reversible blade holders arranged to the side of the under-running portion of the strop, a corresponding row of blade holders arranged to the side of the over-running portion of the strop, and automatically operating means for simultaneously reversing the positions of all of the blade holders.

12. In a machine of the class described, the combination with an endless flexible 110 strop, of automatically operating means for intermittently moving the strop in reverse directions, a series of reversible blade holders adapted to hold the edges of razor blades against the inner and outer surfaces of said 115 strop, and automatically operating means actuated at the ends of the intermittent movements of the strop for reversing the positions of all of said blade holders.

In testimony whereof I hereunto affix my 120 signature in the presence of two witnesses, this 16th day of November, 1911.

WELCOME F. SWEET.
